UNITED STATES PATENT OFFICE

2,528,922

CIRCUIT MAKER AND BREAKER

Frank A. Talbot, Baltimore, Md., assignor of one-half to Robert E. Barry, Washington, D. C.

Application December 12, 1946, Serial No. 715,668

9 Claims. (Cl. 200—116)

1

This invention relates to improvements in circuit makers and breakers, and more particularly to a snap-action lighting switch of rugged construction which provides safety, dependability, minimum maintenance and positive operation for use in locations where atmospheric conditions are adverse.

One of the objects of the invention is to provide a novel snap-action mechanism applicable to various kinds of switches.

A further object is to supply a lighting switch, the contacts of which may be immersed in oil, and a switch provided with novel thermostatically-controlled means for short circuit and overload protection.

Another object of the invention is to furnish a switch of this character having an operating lever of trim design, but large enough to provide a good, comfortable grip assuring positive and easy operation, and one which may be used to indicate the electrical position of the switch so long as the thermostatic control is in a certain position.

A further object is to supply the switch with renewable contacts—heavy duty, series break. This large contact area and series break prevents the concentration of burning. In accordance with the invention, the contacts are self-aligning-constant pressure.

A still further object is to provide a snap-action switch including a contact actuator, that is constantly urged to open-switch position, but normally held in closed position by a thermostatically-controlled latch.

With the foregoing objects outlined and with other objects in view, which will appear as the description proceeds, the invention consists in the novel features hereinafter described in detail, illustrated in the accompanying drawings, and more particularly pointed out in the appended claims.

In the drawings:

Fig. 1 is a side elevation, partly in vertical section, of one embodiment of a switch in accordance with the invention.

Fig. 2 is a rear elevation of the same.

Fig. 3 is a front elevation with the switch in closed position and with the thermostatically-controlled latch in latched position.

Fig. 4 is a view like Fig. 3 with a front cover removed and showing the switch in open position and the thermostatic latch in unlatched position.

Fig. 5 is a front elevational view of a modification of the snap-action mechanism shown

2

connected to an operating means and a contact carrier, with parts broken away to facilitate illustration. In this view, the switch is shown in closed position.

5 Fig. 6 is a top plan view and Fig. 7 an end view, respectively, of the structure shown in Fig. 5.

Fig. 8 is a view similar to Fig. 5 but showing the switch in open position.

10 Fig. 9 is an end view and Fig. 10 a side elevation, respectively, of a pin forming part of the mechanism illustrated in Figs. 5 to 8, inclusive.

Referring to the switch illustrated in Figs. 1-4 of the drawings, 10 designates a panel of insulating material adapted to be fixedly arranged in an upright position in any suitable casing (not shown), so the lower portion of the mechanism may be immersed in oil.

15 A cover or face plate 11 is positioned forwardly of the panel and is rigidly connected with spacing arms 12, detachably secured to the panel by means of screws 13 or the like. The arms act to rigidly support the plate 11 and to space it from the panel.

20 A horizontal rock shaft 14 is journalled in the face plate and provided at the front end thereof with an operating lever 15, of trim design, but large enough to provide a good grip to assure positive and easy operation of the shaft. Such handle may be employed with indicia (not shown) on the plate 11 to indicate whether the switch is open or closed.

25 A toggle actuator 16 is fixed to the shaft and is provided at its top with a nose or cam 17 to engage and cooperate with pairs of toggle links 18 and 19. The links 18 are fulcrumed at one end on a fixed pivot 20 supported by the plate 11, and the links 19 are pivotally mounted at one end on a fixed pivot 21, also supported by said plate. The opposite ends of the links are pivotally connected respectively at 22 and 23 to opposite lateral arms 24 and 25 of a three-armed lever 26. The lever has a centrally disposed slot 27 for the reception of a stud 28 which projects forwardly from the upper end of a contact carrier or actuator 29. The stud is pivotally connected to the part 29.

30 The third or upwardly extending arm 30, of the three-armed lever, is connected to one end of a coil spring 31, the opposite end of which is anchored to the top portion of the plate 11 so that the spring acts to move the three-armed lever either in clockwise or counter-clockwise direction after the arm 30 has swung either to the left or right after passing dead center, in piv-

oting on the stud or pin 28. The latter is fixedly mounted on the upper end of a substantially triangular lever 32, rotatably supported on the shaft 14. As the pin 28 extends into the slot 27, it will be obvious that each time the three-armed lever 26 is shifted, the pin 28 will also be shifted either to the right or left, and in order to insure snap-action, a coil spring 33 surrounds the shaft 14 and has its ends extending into notches 34 and 35 of the respective forward extensions 36 and 37 of the actuator 16 and the lever 32.

The medial portion of the contact carrier 29 is pivotally connected to a stud 38 which projects entirely through the contact carrier and forms a latch element 39 at the front thereof (Fig. 1). The opposite end portion of the stud 38 extends through a hole 40 of larger diameter than the stud, in the panel 10, and is fixedly connected to an oscillating member or support 41, pivotally mounted at 42 on the rear of the panel. A coil spring 43 (Fig. 2) has one of its ends anchored to the oscillating member at 44 and its opposite end anchored to a fixed terminal 45 at the rear of the panel. Due to this construction, the spring 43 tends to constantly move the contact carrier 29 in a clockwise direction (Fig. 2) about the fulcrum pin 28, from which the contact carrier is suspended.

The contact carrier 29 fixedly carries at its lower end, a bracket 46 having an aperture to slidably receive a shaft or rod 47 having a head 48 at one end to limit the movement of the bracket in one direction. A contact bridge 49 is loosely mounted on the rod between a cotter pin 50, extending through a hole in the rod, and a coil spring 51 that abuts at one end against the bracket 46 and at the other end against the bridge. The rod also moves axially in a guide hole extending through a bracket 52 held in place by cylindrical contacts 53 and 54, removably fixed to the front of the panel and arranged at right angles thereto. The bracket 52 is of insulating material so that current cannot pass from the lead-in contact 54 to the contact 53 when the switch is open, but, when it is closed, allows the current to flow from 54 through the bridge 49 to the contact 53.

A stud 55 is fixed to the front of the panel, to be contacted by the lower end of the contact carrier 29 to limit opening movement of the switch.

A bi-metallic or thermostatic element has legs 56 and 57 connected to a lower transparent face plate 58 (supported by the contacts 53-54), as shown in Figs. 1, 3 and 4, and the leg 56 is in electrical connection with the contact 53. These legs are of L-shape (Fig. 1) with curved portions 59 arranged adjacent the bends therein and the horizontal portions 60 of the legs are connected to one another, as indicated at 61. The linking portion 61 of the bi-metallic element carries a depending latching element 62, cooperating with the latching element 39 to hold the contact carrier 29 in a certain position so long as the bi-metallic element is in normal position, or the full line position shown in Fig. 1. When the thermostatic element is affected by conditions in the line, heat will cause the part 61 to rise to the dotted line position (Fig. 1), so that the part 62, will release the latch element 39 and allow the spring 43 to shift the contact carrier to open-switch position, as indicated in Fig. 4.

Current leaves the switch through a terminal 63 in electric contact with the legs 57 of the thermostatic element.

In operation, assuming that the switch is closed, as indicated in Fig. 3, and the thermostatic latch element 62 is in engagement with the latch element 39 of the stud 38, on which the contact carrier 29 pivots, if the operating member or handle 15 is moved counter-clockwise, the nose or cam 17 will engage and raise the ends of the toggle links 18 which turn counter-clockwise about the pivot point 20. At the same time, the actuator 16, in moving counter-clockwise, will act by means of its extension 36 on one leg of the spring 33, to tension the latter while the member 32 remains stationary. As soon as the pivot point 22 rises sufficiently to turn the arm 30 of the three-armed lever clockwise, beyond dead center, the spring 31 will act to throw the arm 30 into the position shown in Fig. 4, and as the toggle mechanism snaps into position, to place the axis of the pivot 23 below the axis of the pivot 22, the spring 33 will recoil so that one of its legs will act on the extension 37 of the member 32 to turn the latter counter-clockwise. As the member 32 carries the pin 28, that pin will act to move the upper end of the contact carrier 29 toward the left, and as the central portion of the contact carrier pivots on the stud 38, it is obvious that the bracket 46 will act on the head 48 of the shaft 47 to move the bridge 49 away from the contacts 53 and 54.

If the handle 15 is now turned in a clockwise direction, an opposite action will take place so as to close the switch.

While the switch is closed, if any disturbance in the circuit should cause the bi-metallic member to act to raise the latch element 62, the contact carrier 29 is automatically turned counter-clockwise about the pivot 28 to open the switch. This action may be readily understood from Fig. 2 where it may be seen that the pin 38, if not held in the full line position by the thermostat, will be caused by the spring 43, to travel with the member 41 counter-clockwise about the pivot 42 so as to shift the contact carrier about the pivot 28 until the lower end of the contact carrier is halted by the stop 55.

As long as the thermostatic element is in the dotted line position shown in Fig. 1, the latch cannot function and hence even though the snap-action mechanism at the upper end portion of the device is actuated, it will have no effect on opening or closing of the switch because the stop 55 will then function as a fulcrum, and the contact carrier will simply turn about this fulcrum when the pin 28 is moved toward the right or toward the left.

In Figs. 5 to 10, inclusive, I have illustrated the snap-action mechanism as used for a large safety switch. This is similar to the switch disclosed in Figs. 1 to 4, inclusive, except for the latching spring and center pin of toggles. In Figs. 5 to 10, 70 indicates a mounting panel through which a horizontal pivot bolt 71 extends. An actuating plate 72 is pivotally mounted thereon rearwardly of the panel, and provided with a rearwardly extending horizontal pin 73 to which is attached a vertically reciprocating handle or operating member 74, employed in oscillating the actuation plate 72 vertically on the bolt.

Arranged at the front of the panel and also pivotally mounted on the bolt, is a driven plate 75. The actuating plate 72 is provided with an arcuate slot 76 arranged concentric to the axis of the bolt.

The plate 75 is provided with a projecting ear 77 in which is journaled a pin 78 (Figs. 9 and

10) having end portions 79 provided with oppositely disposed flat sides 80. The flat sided ends of the pivot pin extend into straight slots 81 provided in front and rear three-armed levers 82 and 83, spaced apart and connected together by pivot pins 84, 85 and 86. A toggle link 87 has one of its ends connected to the pin 84 and its opposite end pivotally connected to a stationary horizontal stud 88 mounted upon the front of the panel 70. Another toggle link 89 has one of its ends pivotally connected to the pin 86 and its other end pivotally connected to a fixed stud 90 projecting from the panel 70.

A slideable stud 91 is pivotally connected to the pin 85 and slides in guide bracket 92 fixed to the front of the panel. A coil spring 93 surrounds the stud and serves to act upon the three-armed levers 82, 83 so as to hold the toggle mechanism in either of its two positions, after it passes dead center. A horizontal stud 94, fixed to the lever 83, projects rearwardly therefrom through a slot 76a in the panel 70, into the registering slot 76 of the actuating plate, and is actuated each time an end of the arcuate slot 76 contacts the pin during the turning of the actuating member by the handle 74. Another horizontal stud 95, fixed to the driven plate 75 projects through an arcuate slot 96 in the panel and is arranged alongside of the pin 73 of the actuating plate.

A coil spring 97 surrounds the pivot bolt 71 and has its end portions crossed at 98, and its legs 99 and 100 arranged at opposite sides of the pins 73 and 99, so that the spring will be tensioned when one of the pins is moved relatively away from the other.

A driven rod 101, which may be formed of parallel plates, has a roller 102 at its upper end movable in a cam slot 103 of the driven plate 75. Power is delivered by the driven member to the rod or link 101 by the cam slot, and such slot is curved to give a variable mechanical advantage, so that high pressure is set up on electrical contacts 104 and 105 by the bridge 106 of the switch after the switch is closed (Fig. 5). In this figure, the mechanism is shown for maximum pressure or while the switch is in the "on" position. Of course, the bridge 106 is carried by the link 101. A swinging link 107 is pivotally connected at one end to the axle of the roller 102, and is pivotally connected at its opposite end to a fixed stud 108, projecting from the front of the panel 70.

In the operation of this modification, it may be seen from Fig. 8 that if handle 74 is depressed to cause the driving member 72 to move clockwise, the pin 73 will move the leg 100 of the spring 97 downwardly so as to tension that spring, and as soon as the lower end of the arcuate slot 76 of the driving member 72 contacts the pin 94, the latter will move with the driving member in a clockwise direction about the axis of the bolt 71. As the stud 94 is fixed to the three-armed lever, the latter will turn in a counter-clockwise direction about the axis of the pin 79 so as to shift the toggle links 87, 89 until the three-armed lever moves over dead center, at which time the spring 93 will function to shift it from the position shown in Fig. 8 to the position shown in Fig. 5, and as the pin 79 connects the three-armed lever to the driven plate 75, the latter will be moved clockwise, under the influence of the spring 97, so as to cause the cam slot 103 to lift the link 101 to compel the bridge 106 to engage the contacts 104 and 105, as shown in Fig. 5.

When the parts are in the position shown in

Fig. 5, they may be returned to the position shown in Fig. 8 by moving the handle 74 upwardly.

From the foregoing, it is believed the construction, operation and advantages of the invention may be readily understood, and it is apparent that changes may be made in the details disclosed without departing from the spirit of the invention, as expressed in the following claims.

10) What I claim and desire to secure by Letters Patent is:

1. In a switch of the character described, a double toggle including a three-armed intermediate lever and a pair of links, one end of one link being turnable about a fixed axis and having its other end pivotally connected to an arm of the three-armed lever, the other link having one of its ends turnable about a fixed axis and its other end pivotally connected to an opposite arm of the three-armed lever, spring means operatively connected to the remaining arm of the three-armed lever and adapted to yieldingly hold the latter in either one of two positions, an actuator operatively connected with the double toggle for initiating movement of the three-armed lever into either one of its two positions, a second spring means operatively connected to the actuator, an operating member for moving the actuator and tensioning the second spring means, a driven member actuated by the second spring means, and a contact actuator driven by said driven member.

2. In a switch of the character described, a double toggle including a three-armed intermediate lever and a pair of links, one end of one link being turnable about a fixed axis and having its other end pivotally connected to an arm of the three-armed lever, the other link having one of its ends turnable about a fixed axis and its other end pivotally connected to an opposite arm of the three-armed lever, spring means operatively connected to the remaining arm of the three-armed lever and adapted to yieldingly hold the latter in either one of two positions, a pivotally mounted actuator operatively connected with the double toggle for initiating movement of the three-armed lever into either one of its two positions, a second spring means operatively connected to the actuator, an operating member for turning the actuator and tensioning the second spring means, a driven member actuated by the second spring means, and a contact actuator driven by said driven means.

3. In a switch of the character described, a double toggle including a three-armed intermediate lever and a pair of links, one end of one link being turnable about a fixed axis and having its other end pivotally connected to an arm of the three-armed lever, the other link having one of its ends turnable about a fixed axis and its other end pivotally connected to an opposite arm of the three-armed lever, spring means operatively connected to the remaining arm of the three-armed lever and adapted to yieldingly hold the latter in either one of two positions, a pivotally mounted actuator operatively connected with the double toggle for initiating movement of the three-armed lever into either one of its two positions, a second spring means operatively connected to the actuator, an operating member for turning the actuator and tensioning the second spring means, a driven member actuated by the second spring means and pivotally mounted for movement about the same axis on which the ac-

tuator turns, and a contact carrier driven by said driven member.

4. In a switch of the character described, a double toggle including a three-armed intermediate lever and a pair of links, one end of one link being turnable about a fixed axis and having its other end pivotally connected to an arm of the three-armed lever, the other link having one of its ends turnable about a fixed axis and its other end pivotally connected to an opposite arm of the three-armed lever, spring means operatively connected to the remaining arm of the three-armed lever and adapted to yieldingly hold the latter in either one of two positions, an actuator operatively connected with the double toggle for initiating movement of the three-armed lever into either one of its two positions, a second spring means operatively connected to the actuator, an operating member for moving the actuator and tensioning the second spring means, a driven member actuated by the second spring means, and a contact carrier operatively connected to the three-armed lever and moved thereby.

5. In a switch of the character described, a double toggle including a three-armed intermediate lever and a pair of links, one end of one link being turnable about a fixed axis and having its other end pivotally connected to an arm of the three-armed lever, the other link having one of its ends turnable about a fixed axis and its other end pivotally connected to an opposite arm of the three-armed lever, spring means operatively connected to the remaining arm of the three-armed lever and adapted to yieldingly hold the latter in either one of two positions, said three-armed lever being provided intermediate its opposed arms with an elongated slot, a pivotally mounted actuator for initiating movement of the three-armed lever into either one of its two positions, a pin pivotally mounted in the actuator and having a flat head slidably mounted in said slot, a second spring means operatively connected to the actuator, an operating member for rotating said actuator and tensioning the second spring means, a driven member actuated by the second spring means, and a contact actuator driven by said driven member.

6. In a switch of the character described, a double toggle including a three-armed intermediate lever and a pair of links, one end of one link being turnable about a fixed axis and having its other end pivotally connected to an arm of the three-armed lever, the other link having one of its ends turnable about a fixed axis and its other end pivotally connected to an opposite arm of the three-armed lever, spring means operatively connected to the remaining arm of the three-armed lever and adapted to yieldingly hold the latter in either one of two positions, a pivotally mounted actuator operatively connected with the double toggle for initiating movement of said lever into either one of its two positions, a second spring means operatively connected to the actuator, an operating member for turning the actuator and tensioning the second spring means, a pivotally mounted driven member actuated by the second spring means and provided with guiding means having a portion tangent to the axis of rotation of the driven member, and a contact actuator operatively connected to said guide means and actuated by said driven member.

7. In a switch of the character described, a double toggle including a three-armed intermediate

lever and a pair of links, one end of one link being turnable about a fixed axis and having its other end pivotally connected to an arm of the three-armed lever, the other link having one of its ends turnable about a fixed axis and its other end pivotally connected to an opposite arm of the three-armed lever, spring means operatively connected to the remaining arm of the three-armed lever and adapted to yieldingly hold the latter in either one of two positions, a pivotally mounted actuator operatively connected with the double toggle for initiating movement of the three-armed lever into either one of its two positions, the axis of the actuator being arranged parallel to the axes of the links, a second spring means operatively connected to the actuator, an operating member for turning the actuator and tensioning the second spring means, a driven member actuated by the second spring means and turnable about the same axis as the actuator, said driven member having a tangentially arranged slot, a roller travelling in said slot, and a contact actuator connected to the roller and driven by the driven member.

8. In a switch of the character described, a supporting panel, a manually controlled mechanism supported by said panel and arranged at one side thereof, a contact actuator having an end portion pivotally connected to said mechanism and operated thereby, a support pivotally mounted on the opposite side of said panel, said panel being provided with an aperture between the point where the support is pivotally mounted and the place where the contact actuator is pivotally connected to said mechanism, a trigger connecting the medial portion of the actuator to said support and extending through said aperture, resilient means connected to the support for constantly urging the contact actuator into open-switch position, and thermostatic means engageable with the trigger and responsive to a condition in the circuit controlled, to prevent the contact actuator from moving in response to said resilient means.

9. In a switch of the character described, a manually controlled mechanism, a contact actuator pivotally connected thereto, a rod slidably supported by the actuator, a bridge slidably mounted on the rod, stationary contacts with which the bridge cooperates to complete a circuit, a spring mounted on the rod and arranged to be compressed when the bridge engages the contacts for yieldingly pressing the bridge against said contacts, resilient means constantly urging the contact actuator and bridge into open-switch position, and thermostatic means in electrical connection with one of said contacts and responsive to a condition in the circuit controlled, to prevent said actuator from moving in response to said resilient means.
